UNITED STATES PATENT OFFICE.

WALTER M. DAVIS, OF NEW YORK, N. Y., AND JUSTUS HATTEMER, OF WEST NEW YORK,
NEW JERSEY, ASSIGNEES TO HARDMAN, PECK & COMPANY, OF NEW YORK, N. Y.,
A CORPORATION OF NEW YORK.

ELECTRIC ACCENTING DEVICE FOR PNEUMATIC MUSICAL INSTRUMENTS.

1,046,275.

Specification of Letters Patent.

Patented Dec. 3, 1912.

Application filed April 14, 1911. Serial No. 621,143.

To all whom it may concern:

Be it known that we, WALTER M. DAVIS and JUSTUS HATTEMER, citizens of the United States, residing at New York, county 5 of New York, State of New York, and West New York, county of Union, State of New Jersey, respectively, have invented certain new and useful Improvements in Electric Accenting Devices for Pneumatic Musical Instruments; and we do hereby declare the following to be a full, clear, and exact description of the invention, such as will enable others skilled in the art to which it 10 pertains to make and use the same.

This invention relates to self-playing musical instruments and has for an object to provide electrically actuated means for accenting the notes of the theme or any other part of the music which it is desired 15 to accent.

A further object of the invention is to provide brushes with improved means for projecting the same over the trackerbar into position for engagement through an opening 20 in the music sheet with contacts carried by the trackerbar and with means electrically connected with such brushes and contacts for actuating the accenting device.

A further object of the invention is to 25 provide, in conjunction with an accent box, as for instance such an accent box as disclosed in Patent No. 902,728 to one of these applicants, valves for controlling primaries which in turn control such accent box with 30 electrical means for controlling the valves and means whereby the electrical means is energized by the passing over the trackerbar of openings in the music sheet.

A further object of the invention is to 35 provide an accent box having a primary with a conduit leading to the primary and a valve for closing the conduit also with an electro-magnet positioned to open the valve when the magnet is energized and an electric circuit including the magnet and contacts adapted for engagement through an 40 opening in the music sheet as the music sheet passes over the trackerbar.

A further object of the invention is to 45 provide improved mechanism for controlling the position of the brush relative to the trackerbar.

With these and other objects in view the invention comprises certain novel construc-

tions, combinations and arrangement of parts as will be hereinafter more fully described and claimed.

In the drawings:—Figure 1 is a view of the improved device diagrammatically shown with the electro-magnets positioned for actuating the manual accent control. Fig. 2 is a view similar to Fig. 1 except that the electro-magnets are located at or near the accent box and control the passage to the primary. Fig. 3 is a perspective fragmentary view showing one of the brushes and actuating means with the brush in operating position upon the contact. Fig. 4 is a perspective view of one of the brushes and actuating means in the first position of being moved from engagement with the contact. Fig. 5 is a perspective view of the brush and actuating means showing the removal of the brush from the contact completed and the brush maintained out of such engaging position.

Like characters of reference designate corresponding parts throughout the several views.

As shown at Figs. 1 and 2, an accent box 50 is employed of any construction, the device as shown being only diagrammatic and illustrative of the invention. As shown, the accent box 10 is controlled by primaries 11 and 12, although it is to be understood that the position and actual operation of such primaries is wholly immaterial to the present invention. Under the primaries 11 and 12, chambers 13 and 14 respectively are provided which communicate by means of passages 15 and 16 with valves 17 and 18.

As shown at Fig. 1, the valves 17 and 18 are carried upon levers 19 and 20 which are ordinarily controlled by manual push buttons 21 and 22. As shown at Fig. 2 the valves 17 and 18 are carried by armatures 23 and 24. In either instance the valves 17 and 18 are controlled by electro-magnets 25 and 26 respectively to open communication through the passages 15 and 16 with the primaries 11 and 12 and thereby actuate the accenting device.

To energize the magnets 25 and 26 a battery 27 is provided with wiring forming circuits extending, as easily apparent at 55 Figs. 1 and 2, to brackets 28 and 29 extending upon opposite sides outwardly from cheek-plates 30 and 31. The brackets 28 and

29 form a bearing for the sliding rods 32 and 33 which also extend and slide through cheek-plates 30 and 31. Upon the ends of the rods 32 and 33, between the cheek-plates 30 and 31, fingers 34 and 35 are rigidly carried, terminating in brushes 36 and 37. When in operative position, as indicated at dotted lines in Figs. 1 and 2, the brushes 36 and 37 are in position for engagement with contacts 38 and 39 preferably flush with the face of the tracker bar 40 but insulated therefrom by the insulating material 41. The contacts 38 and 39 are in circuit with the battery 27 and the electro-magnets 25 and 26, as will be easily seen.

When changing music it is desirable that the brushes 36 and 39 be removed from position for engagement with the sheet and it is also desirable at times to have such brushes removed to prevent mechanical accenting of the music and to permit manual accenting. For these purposes the rods 32 and 33 are provided with the arms 42 and 43 which slide along the edge of the brackets 25 28 and 29 and when the brushes are in operative position are seated in the notches 44 and 45. The arms are held within such notches yieldingly by means of springs 44' and 45' which serve not only to hold the levers within the notches 44 and 45 but by reason of their angular position, also to hold the brush yieldingly in engagement with the contacts 38 and 39. To remove such brushes backwardly out of engagement with the contacts, the rods 32 and 33 are also provided with fingers 46 and 47 engaged by the hooked ends 48 and 49 of rods 50 and 51 journaled at the side of the cheek-plate in any approved manner as by the blocks 52.

40 The rods 50 and 51 are provided respectively with arms 53 and 54 connected by the link 55 so that both of such levers operate together in unison to simultaneously move the brushes 36 and 37. A link 56 is also 45 preferably provided, connected in any approved manner with the rewind lever so that when the rewind is actuated the brushes are automatically removed. As such connection forms no part of the present invention however, it is not here illustrated.

It will be apparent that with the brushes 36 and 37 in engagement with the contacts 38 and 39, when an opening in the music sheet passes over such contact, the brushes 55 will engage the contact and close the circuit through the battery 27 and electro-magnets 25 and 26, dependent upon whether the brush 36 or 37 is at that instant permitted to engage its contact. By the arrangement 60 of marginal openings upon the music sheet, properly spaced, the magnets 25 and 26 are energized at the proper instant to actuate the primaries 11 and 12 to in turn actuate

the accenting device which may be of any ordinary and approved construction.

With the brush located as indicated at Fig. 3, it is apparent that such brush is in engagement with its contact. The first movement of releasing such brush from such engagement is illustrated at Fig. 4, which by reason of the peculiar shape of the hook 48, first rotates the rod 32 by depressing the finger 46 to release the lever 42 from the notch 44 and simultaneously to lift the brush 36 from engagement with the music sheet. This frees the brush from contact which might injure the brush. The further rotation of the rod 50 forces the rod 32 back to the position shown at Fig. 5 whereat the spring 46 draws the rod 32 to such position that the finger 46 is retained substantially back of the axis of the rod 50 and is not released to permit the brush to return to operative position until the rods 50 and 51 are manually operated. In other words, when the brush has been moved to the position shown at Fig. 5 it is automatically retained in that position by the engagement of the finger 46 behind the bend of the rod 50 until the rod 50 is manually returned to position shown at Fig. 3. The action to release the brush from the music sheet is, then, first a turning movement of the rod 32 and a lifting movement of the finger 34, as indicated at Fig. 4, whereby the brush is released from engagement with the music sheet and trackerbar and then the brush and its carrying rod 32 moved slidably backward to the position shown at Fig. 5 and all by the simple continued turning of the rod 50.

We claim:

1. In a pneumatic player for musical instruments, the combination of a pneumatic accenting device, of manual means for controlling the accenting device, and electrical means controlled from the trackerbar for actuating the manual apparatus.

2. In a pneumatic player for musical instruments, a pneumatic accent box, a conduit leading from the accent box and terminating in a port, a manual lever carrying a valve controlling the port, electrical means for actuating the lever, and contacts located at the trackerbar adapted to close the circuit through perforations in a traveling music sheet.

In testimony whereof we affix our signatures in presence of witnesses.

WALTER M. DAVIS.
